UNITED STATES PATENT OFFICE.

WILLIAM W. FLICKINGER, OF BRADFORD, PENNSYLVANIA.

POWER APPARATUS.

No. 863,839.

Specification of Letters Patent.

Patented Aug. 20, 1907.

Application filed July 13, 1905. Serial No. 269,545.

To all whom it may concern.

Be it known that I, WILLIAM W. FLICKINGER, a citizen of the United States, residing at Bradford, Pennsylvania, have invented certain new and useful Improvements in Power Apparatus, of which the following is a specification.

My invention relates to power applying plants and it is designed for instance to supply compressed air or other gases for use in all situations where this may be required, as for example in driving oil pumps from a central station or reservoir, the said plant or apparatus also being arranged to drive machinery more closely associated therewith, such as in the same factory or shop in which the plant or apparatus is located.

15 The invention includes an explosive engine having means for transmitting power, such as a crank shaft adapted to be belted or connected in any other suitable manner to nearby machinery or apparatus to drive the same, the said explosive engine being adapted also to compress air which is stored in a suitable reservoir or tank, and is adapted to be drawn therefrom to drive any apparatus as may be desired, either nearby or at a distant point, such for instance as in an oil field where widely separated pumps are required to be 25 driven from a central stored source of power.

20 My invention includes also means whereby the air compressing portion of the cylinder may be filled with air to its full capacity so that on the compression stroke the piston will have a full supply or volume of air to 25 operate against and compress.

The invention consists in the features and combination and arrangement of parts hereinafter described and particularly pointed out in the claims.

30 In the accompanying drawings, the figure is a part sectional view and part side elevation of an explosive engine embodying my improvement.

35 In these drawings the explosion chamber is indicated at 3. Any suitable igniting devices may be employed and suitable ports and valves are provided for the explosive mixture and for the exhaust.

40 I close the front end of the cylinder by a plate 4 and in this way provide an air compressing chamber 5, the piston 6 which is closed at each end serving both as the motor piston and as the air compressing piston.

45 The piston rod 7 passes through the stuffing box in the head or plate 4 at the front end of the engine cylinder and is connected with a crank shaft 11 carrying a fly-wheel 12.

50 The air compressing end of the cylinder is provided with a valved air inlet port 13 to which leads an air suction pipe 14 and allows the air to flow into the chamber 5 when the piston 6 is on its back stroke. This end of the cylinder is also provided with an air outlet pipe 16 leading from a port 17 controlled by an air discharge 55 valve 18, of any suitable form. The air outlet 16 leads to a reservoir 19 which I have shown only diagram-

matically, and in this reservoir the air compressed by the action of the piston 6 is stored to be drawn off as desired, through any suitable pipes leading to the apparatus or machine to be operated by the compressed air. It will be seen that I utilize the same cylinder which is of the same diameter its entire length in which the motor piston is located for the purpose of air compression and this is also true of the engine piston, that is the one piston serves as the piston for the explosion chamber and for the compression chamber and from the same engine I am enabled to transmit power in two different ways, that is by the compressed air and also by the crank shaft in any ordinary manner. I also provide means for introducing air into the air compression chamber to destroy the partial vacuum which exists at the end of the suction stroke. This consists of the port 29 from which leads the pipe 30. This port and pipe are uncovered at the end of the piston stroke in each direction. On the forward stroke of the piston the uncovering of this port allows the spent gases or foul mixture to discharge through the pipe 30 which then acts as the exhaust. When the piston is on its backward stroke compressing the fresh charge of explosive mixture for the explosion, this port 29 is also uncovered as this stroke terminates. During this stroke the air has been sucked in through the port 13, but a partial vacuum would exist ordinarily if some means were not provided to destroy this at the end of the backward stroke of the piston, and in my present form the destroying of this vacuum is accomplished by the air that passes through the pipe 30 and port 29 into the air compression chamber. The piston is provided with a shoe or projection 31 on each end and in the final movement on each stroke the appropriate shoe or projection uncovers the port 29. When the piston is compressing air the port is

35 also open at the extreme end of the suction stroke, allowing the air which has a slight pressure from the previous exhaust without mechanical means or loss of power in any way to rush in and destroy the vacuum and thus giving the air cylinder its full capacity at every stroke. The filling of the air cylinder is aided because of the fact that there is a little pressure on the exhaust pipe at the time the port is uncovered. This 40 permits a much higher speed to the compressor as the principal objection to running compressors at high speed is that the vacuum existing at the end of the suction stroke greatly reduces the efficiency of the compressor. This feature is especially valuable for explosive motors as the latter are better adapted to high speeds and in fact it is necessary to run them at high speed to make them efficient.

I claim as my invention:

1. In combination in an air compressing engine, a cylinder, a piston, means for admitting motive fluid to one end of the cylinder air inlet and discharge means for the

other end whereby the air is drawn in on one stroke and discharged on the reverse stroke, means for destroying the partial vacuum as the piston reaches the end of its suction stroke, said means consisting of a port so located as to be

5 uncovered as the piston completes its stroke in either direction, thereby acting on one stroke as an exhaust port and on the opposite stroke as an air inlet port, substantially as described.

2. An engine of the class described, comprising a cylinder, suction and discharge ports at one end of the cylinder, means for admitting motive fluid to the other end of the cylinder, a piston having a projection or shoe on

each end, and a port over which said projections or shoes slide to be uncovered thereby both on the suction and compression strokes, said port being so located as to act as an 15. exhaust for the spent explosive mixture and as an air inlet substantially as described.

In testimony whereof, I affix my signature in presence of two witnesses.

WILLIAM W. FLICKINGER
